METERING DEVICE

William Collins Brinton, Jr., Harper, Wash.

Application July 20, 1929, Serial No. 379,696
Renewed January 28, 1933

5 Claims. (Cl. 221—95)

This invention relates to a metering device particularly adapted for the delivery of measured quantities of granular or pulverized materials, such as coffee, tobacco, sugar, cement, sand, or the like.

The broad object of the present invention relates to the provision of a metering device which is of simple construction and which will serve to dispense fairly accurate predetermined quantities of granular or fine solid materials. The invention is particularly adapted to the construction of a cap for jars or other containers which may contain granular material to be dispensed.

Detailed objects of the invention relating to advantageous features of construction will become apparent from the following description when read in conjunction with the accompanying drawing, in which:

Fig. 1 is a transverse section through one embodiment of the invention consisting of a metering cap;

Fig. 2 is a plan view of the subject of Fig. 1;

Fig. 3 is a section similar to Fig. 1 showing the device in discharging position; and

Fig. 4 is a section on line 4—4 of Fig. 2.

In the embodiment which is disclosed herein, the invention is shown as applied to a cap for a jar or similar container. The jar is indicated at 2 as provided with a threaded neck for the reception of a cap 4 which is formed, as indicated at 6, with an inwardly turned flange. This flange serves to support a spiral spring by engagement with an intermediate convolution thereof. This spiral spring comprises two parts 8 and 10, the former consisting of a tension spring and the latter of a compression spring. The spring is secured to the flange at 6 in any desired manner, either merely by engagement of the convolutions with the flange or by soldering or clamping the convolutions in any desired fashion. In view of the fact that the portion 10 of the spring normally tends to expand while portion 8 tends to contract, the normal position of the spring will be as indicated in Fig. 1.

An annular member 12 secured to the cap, as indicated in the figures, carries upstanding ears in which is secured a removable pin 14 serving as a pivotal support for a lever 16, the outer end of which is provided, as indicated at 17, with a turned portion adapted to be engaged by the finger of a user of the device. Secured to the other end of the lever 16 is a disc shaped cover 18. The outer convolution of portion 8 of the spring is clamped between the cover disc 18 and a plate 20 secured to the cover. The plate 20 is secured,

as indicated at 22, with a series of links or the like 24 to a valve disc 26 forming, as indicated at 28, a seat for the end convolution of spring 10. A cage 30, formed of wire, serves to guide the valve disc and the portion 10 of the spring during inward movement, as indicated in the figures, the wire cage being formed of cross wires secured at their inner ends to the cap in any suitable fashion as, for example, by soldering. In the present embodiment the ends of wires 30 are turned, as indicated at 34 in Fig. 4, and enter beneath an upwardly extending stamped portion pressed out of the flange of the cap. As will be obvious from this figure, movement of the wires outwardly is prevented by the stamped out portion of the cap, whereas inward movement is prevented by contact with flange 6 and the convolutions of spring 10.

A spout 32 of semi-cylindrical form may be secured to cap 4 to serve to guide the contents during discharge.

In the operation of the device, when the container is upside down, as indicated in Fig. 1, it will be seen that the convolutions of portion 10 of the spring are spaced far apart, while the convolutions of portion 8 are close together. When in the position indicated in Fig. 1, the granular or other material will flow into the space between the cover 18 and valve 26. If pressure is now applied to the turned end 17 of the pivoted lever 16, the cover 18 will be swung about 14 as a pivot, thereby tensioning portion 8 of the spring and compressing portion 10 thereof, inasmuch as the cover and valve are connected together by a link 24. During the initial part of the opening, the convolutions of the portion 8 will be drawn apart, while the convolutions of the portion 10 will be brought together. However, the granular material, such as ground coffee or tobacco, or the like, will not flow through the partially open convolutions, due to the arcing effect of this granular material, whereby sufficient friction is imposed to prevent a free flow between the partially spaced convolutions. Likewise, as the convolutions of portion 10 are brought together, flow into the interior of the spring of material from the container is prevented. As further opening occurs, the convolutions of portion 10 are brought closer together, thereby completely preventing flow of material from the container, while the convolutions of portion 8 of the spring are moved farther apart whereby a discharge of the material contained within the spring and between the cover and valve is permitted. By reason of

this action, whereby passage of the granular material within the spring is prevented prior to the discharge therefrom, fairly accurately metered quantities of the granular material will be discharged during each operation, the discharge being proportional to the contents of the space within the spring and between the cover and valve at the time when flow therinto from the container is cut off.

10 While portions 8 and 10 have been shown as forming a part of the same spring, inasmuch as this type of construction is very simple, it will be obvious that the two portions may be separate springs. Accordingly, these two portions are defined as separate springs in the claims, unless their integral connection is brought out.

15 It will be clear that, while the invention has been disclosed as applied to a cap for a container, the invention is equally applicable in the 20 construction of a discharge spout for a bin or the like.

What I claim and desire to protect by Letters Patent is:

1. A metering device for a container provided 25 with an opening, including cover means consisting of a cover mounted on the container and a spiral spring surrounding the opening and seated on the cover, the convolutions of the spring being normally close together whereby the opening is 30 closed, and valve means connected with the cover means for movement therewith and arranged to form with the cover means a measuring chamber, said cover and valve means being so arranged that when the cover means closes the opening, 35 the measuring chamber communicates with the container, and when the cover means is positioned to permit discharge from the opening by spreading of the convolutions of the spring upon movement of the cover communication between the 40 measuring chamber and container is cut off and discharge from the measuring chamber effected.

2. A metering device for a container provided 45 with an opening, including cover means consisting of a cover mounted on the container and a spiral spring surrounding the opening and seated on the cover, the convolutions of the spring being normally close together whereby the opening is 50 closed, and valve means connected with the cover means for movement therewith and arranged to form with the cover means a measuring chamber, said cover and valve means being so arranged that when the cover means closes the opening, the measuring chamber communicates with the container, and when the cover means is positioned to permit discharge from the opening by 55 spreading of the convolutions of the spring upon movement of the cover the communication between the measuring chamber and container is cut off and discharge from the measuring chamber effected, said discharge taking place subsequently to the cutting off of communication between the measuring chamber and container.

3. A metering device for a container provided 60 with an opening, including cover means normally serving to close the opening, and valve

means, comprising a valve member and a spiral spring surrounding the opening and seated on the valve member, said valve means being connected with the cover means for movement therewith and arranged to form with the cover means a 80 measuring chamber, said cover and valve means being so arranged that when the cover means closes the opening, the measuring chamber communicates with the container by reason of the spacing of the convolutions of the spring, and when the cover means is positioned to permit discharge from the opening the communication between the measuring chamber and container is 85 cut off by close arrangement of the convolutions of the spring and discharge from the measuring chamber effected.

4. A metering device for a container provided with an opening, including cover means normally serving to close the opening, and valve means, comprising a valve member and a spiral spring surrounding the opening and seated on the valve member, said valve means being connected with the cover means for movement therewith and arranged to form with the cover means a measuring chamber, said cover and valve means being 90 95 100 so arranged that when the cover means closes the opening, the measuring chamber communicates with the container by reason of the spacing of the convolutions of the spring, and when the cover means is positioned to permit discharge from the opening the communication between the measuring chamber and container is 105 cut off by close arrangement of the convolutions of the spring and discharge from the measuring chamber effected, said discharge taking place subsequently to the cutting off of communication between the measuring chamber and container.

5. A metering device for a container provided with an opening, including cover means consisting of a cover mounted on the container and a 110 spiral spring surrounding the opening and seated on the cover, the convolutions of the spring being normally close together whereby the opening is closed, and valve means, comprising a valve member and a second spiral spring, integral with 115 the first mentioned spring, surrounding the opening and seated on the valve member, said valve means being connected with the cover means for movement therewith and arranged to form with the cover means a measuring chamber, said cover and valve means being so arranged that when the cover means closes the opening by reason of the close arrangement of the convolutions of the first 120 spring, the measuring chamber communicates with the container by reason of the spacing of the convolutions of the second spring, and when the cover means is positioned to permit discharge from the opening by spreading of the convolutions of the first spring, the communication between the measuring chamber and container is 125 130 135 cut off by close arrangement of the convolutions of the second spring and discharge from the measuring chamber effected.
